UNITED STATES PATENT OFFICE.

KELLY M. TURNER, OF LOS ANGELES, CALIFORNIA, ASSIGNOR OF ONE-THIRD TO FRED H. KOCH AND ONE-THIRD TO ESTEN M. ROLAND, BOTH OF LOS ANGELES, CALIFORNIA, AND ONE-THIRD TO YALE CORPORATION, OF LOS ANGELES, CALIFORNIA, A CORPORATION OF CALIFORNIA.

MAGNETO-BRUSH AND FORCE-FEED ATTACHMENT FOR INTERNAL-COMBUSTION ENGINES.

Application filed July 26, 1922. Serial No. 577,651.

To all whom it may concern:

Be it known that I, KELLY M. TURNER, a citizen of the United States, residing at Los Angeles, in the county of Los Angeles 5 and State of California, have invented new and useful Improvements in Magneto-Brush and Force-Feed Attachments for Internal-Combustion Engines, of which the following is a specification.

10 The object of this invention is to provide a satisfactory construction for that class of combined force feed oilers and contact holders, adapted for internal combustion engines, to take the oil thrown by a magneto 15 rotor from the bottom to the top of the transmission or reservoir case and to force such oil onward so that the oil may flow to any bearing part of the engine desired.

In the type of force feed oilers to which 20 this invention appertains the feeding device which catches the oil thrown from the magneto rotor is arranged at the highest point of the housing, containing such rotor and it is customary with many engines to 25 apply the magneto contact member at such elevated point; and an object of this invention is to provide an improved force feed oiler of simple and compact construction and arrangement to be inserted into the ori- 30 fice ordinarily occupied by the fitting which carries the magneto contact member.

The invention consists in a construction and arrangement of the contact holder and oil catching and delivering device in which 35 the contact member is contained in a hollow member that also contains a spring which acts upon the contact member to hold it in contact with the fixed element of the rotor assembly; the container being provided with 40 a threaded stem which serves as a binding post and extends through the outer end of the oil catcher and is insulated therefrom by simple, cheap and easily applied insulating washers or other suitable provision.

45 An object is to provide a device of this kind which is easily manufactured and is certain in operation and will not get out of order.

Other objects, advantages and features of 50 invention may appear from the accompanying drawing, the subjoined detail description and the appended claims.

The invention may be constructed in various forms:

The accompanying drawing illustrates the 55 invention in a form at present deemed most desirable.

Figure 1 is a fragmental view showing a fitting constructed in accordance with this invention and applied to an internal combustion engine, fragments of which are shown.

Fig. 2 is a top plan of the device, detached, with bolts in place.

Fig. 3 is a bottom plan of said device, 65 omitting the bolts.

Fig. 4 is an axial section on line x 4, Figs. 2 and 3 on an enlarged scale.

The fitting comprises a barrel 1 provided with an outlet 2 and having its lower end 70 open as at 3 and provided with the usual lip or projection 4 to catch oil thrown from and by the rotating portion or member *a'* of the magneto and to direct it into the barrel from which it flows through the outlet 2 75 into the oil pipe *b*. The head or top *t* of the barrel 1 is provided with a central orifice 5 and with an insulating washer seat 6 on the upper side of the barrel top, and an insulating washer seat 7 on the underside of 80 such top.

A flange 8 at the bottom of the barrel and above the lip is provided with bolt holes 9 through which bolts 10 are passed in the usual way to fasten the fitting to the engine 85 housing *h*. The contact member 11 is shown as a cylindrical plunger having a cylindrical head or enlargement 12 at one end and a contacting point 13 at the other end.

The contact holder is preferably cylindrical and comprises a casing 14 terminating at its upper end in a shoulder 14' and a threaded stem 15 which extends through the orifice 5 in the top of the barrel and serves as a binding post for the electric wire *w*. 90

A spring 16 is provided in the hollow contact holder to act upon the head 12 of the contact element to yieldingly hold such element extended and in contact with the contact element *c* of the magneto stator *a'*. 100

The head 12 and body 11 fit the inside walls and the inner tip 17 of the hollow contact holder casing. Said tip is contracted by suitable means, as by swaging or by spin-

ning the open end, or in some other suitable manner, to an internal diameter less than the head of the contact member and preferably to a sliding fit on the body of such member; and the spring 16 yieldingly holds the contact member in positive contact with the element *c*.

The circumferences of the insulating washers 18, 19 preferably fit the washer seats 6 10 and 7 and are centrally arranged, and stem 15 and the holes 20 through the washers are of less diameter than the orifice 5 through the top of the barrel, and said stem preferably fits the holes 20 and is thus held free 15 from contact with the barrel; and the contact holder is fastened in place by a nut 21 screwed onto the stem 15, and against the outside washer 18, thus drawing the shoulder 14' of the casing tight against the inner 20 washer 19 and the washers 18 and 19 tight against the top *t* of the barrel so that the contact member is held against lateral displacement relative to the barrel. The holes 25 9 are conformed in position to the holes, not shown, originally provided in the housing to receive the bolts that fasten the usual contact holder in place.

In practice the lip 4 extends downward from the flange 8 in a semi-circle around the 30 casing and down into the engine housing to catch the oil in the usual manner and the operation of the contact member and of the oil delivery is practically the same as with devices of this character heretofore known.

35 The binding post nut 21' serves to bind the wire *w* against the nut 21 and also to secure the attachment from jarring loose.

I claim:

40 1. In an attachment for internal combustion engines substantially set forth, an oil receiving and discharging barrel open at one end and adapted to catch oil, and provided with a central orifice opposite such open end, and also provided with an outlet; 45 a flange at the bottom of the barrel; a lip in the form of a semi-circle extending downward from said flange; a contact holder terminating at its upper end in a shoulder and provided with a threaded stem extending 50 through said central orifice provided in the oil receiving and discharging barrel; a spring in said holder; a contact member arranged in said holder and held by said spring to yieldingly extend from said holder; means to retain said contact member in said contact holder; washer seats above and below said central orifice; insulating washers in said seats and through which said threaded stem passes; and a nut threaded 55 on said stem and adapted to clamp said washers in said seats between said nut and the shoulder on said contact holder.

60 65 2. In combination with a barrel adapted to receive oil thrown from a rotor and to deliver such oil to an outlet attached to any

part of an engine; a contact member; a holder therefor having a stem, said stem extending through the closed end of the barrel; said contact member having an enlargement inside the holder and said holder being contracted beyond the enlargement to hold the contact member; and a spring in the holder to yieldingly hold the contact member extended from the holder.

3. In a combined force feed oiler and magneto contact attachment for internal combustion engines, an oil receiving and delivering barrel open at one end and having oil catching means and an oil outlet; a contact holder provided with a threaded stem out of contact with, and extending through the closed end of the barrel; insulating means on said stem inside and outside the barrel head; a contact member in the holder, and a nut on the stem to fix the insulating means onto the closed end of the barrel and to fix the stem to the closed end of the barrel.

4. The combined force feed oiler and magneto contact attachment set forth comprising a barrel open at one end and there provided with oil catching means and an oil outlet, and also provided with an orifice in the top and with seats for insulating means on the upper end under sides of said top; insulating means in said seats, each provided with a hole of less diameter than the orifice in the top of the barrel; a hollow contact holder reduced to form a threaded stem extending through the washer and the orifice and held by the washers from contact with the dome; a contact member having a head inside the holder; a spring in the holder to yieldingly hold said member extended, the open end of said holder being contracted to support said member and to retain the head thereof; and a nut for securing the stem to the insulating means and such means to the seats at the top of the barrel.

5. In a combined force feed oiler and magneto attachment for internal combustion engines comprising an oil receiving and delivering barrel and an oil catching lip, a contact holder having a chamber; a spring in said chamber; a contact member having a head in the chamber, said member extending from the chamber, said chamber being contracted to retain the head of said member; an oil receiving and delivering barrel; and insulating means to retain the contact holder in the barrel and out of contact therewith.

6. The contact holder for a force feed oiler fitting, comprising a hollow casing provided at one end with a stem and having its other end contracted; a contact member projecting from, and having a head in the casing; said casing being contracted to retain the contact member; and a spring in the casing acting upon the head of such member to hold said member extended; said stem being threaded to receive nuts and

adapted to serve as a binding post for a wire of an electric circuit.

7. In a combined force feed oiler and magneto attachment for internal combustion engines, an oil receiving and delivering barrel being open at one end, and provided with a central orifice through the top at the other end of said barrel; a flange at the bottom of the barrel provided with bolt holes; 5 a lip projecting downward from said flange; 10 a contact holder having a shoulder and a

stem extending through said orifice; insulating washers above and below the top of said barrel; means on said stem adapted to clamp the washers against said top and between said shoulder and said means; and a contact member yieldingly mounted in said contact holder. 15

In testimony whereof, I have hereunto set my hand at Los Angeles, California, 20 this 19th day of July, 1922.

KELLY M. TURNER.
